INTERNAL-COMBUSTION HEATER WITH
AIR-HEATING TUBES

Henry J. De N. McCollum, Chicago, Ill.; Thelma McCollum, executrix of said Henry J. De N. McCollum, deceased, assignor to Stewart-Warner Corporation, Chicago, Ill., a corporation of Virginia

Application April 5, 1943, Serial No. 481,835

3 Claims. (Cl. 126—109)

1

My invention relates to heaters and more particularly to heaters of the type used to heat the cabins or other spaces of airplanes or for similar purposes.

An object of my invention is to provide a heater having a new and improved heat exchanger.

Another object of my invention is to provide a heater having a new and improved combustion chamber.

Another object of my invention is to provide a new and improved heater which is highly efficient, light in weight and which may be easily and inexpensively manufactured.

Other objects and advantages will become apparent as the description proceeds.

In the drawings:

Fig. 1 is a longitudinal, sectional view of a heater embodying my invention and is taken generally along the line 1—1 of Fig. 4, but has certain parts cut away to show details of construction of the tubing of the heat exchanger and the shell of the muffler;

Fig. 2 is a top plan view on a reduced scale of the heater of Fig. 1 and a blower for supplying air thereto, parts being cut away to show the detail of the heat exchanger and induction tube therefor;

Fig. 3 is a transverse, sectional view taken on the line 3—3 of Fig. 1;

Fig. 4 is an irregular, transverse, sectional view taken on the line 4—4 of Fig. 2;

Fig. 5 is a partial view similar to Fig. 3, but showing a modified form of my invention;

Fig. 6 is a perspective view of a part of one of the pipe supporting rings of the heat exchanger;

Fig. 7 is a view showing one step in the assembly of the heat exchanger; and

Fig. 8 is a view showing a subsequent step in the manufacture of this heat exchanger.

In Fig. 2, I have illustrated my novel heater 18 as being supplied with air by a blower 12 driven by an electric motor 14, although a ram or any other suitable source of air supply may be provided in lieu of the blower shown in this figure. As best shown in Fig. 1, this heater comprises a combustion chamber 16 having an end wall 18 and a cylindrical wall 20 attached to one end of a heat exchanger 22 by bolts 24, or any other suitable means. The combustion chamber 16 and the heat exchanger 22 are attached to a cylindrical casing 26 by straps 28 and one end of this casing 26 has a tapered inlet 30 connected to the blower 12.

The heat exchanger 22 comprises a pair of supporting rings 32 and 34 and a plurality of tubes

2

36 mounted thereon. As best shown in Figs. 3 and 4, the tubes 36 are arranged in the form of a cylinder and the contacting walls of adjacent tubes are welded or soldered together, as indicated at 38, so that the entire bundle of tubes forms an air tight cylinder.

A convenient and suitable method of making the heat exchanger 22 is indicated in Figs. 6, 7 and 8. In Fig. 6, I have shown a ring 32 before the tubes are mounted therein. This ring has a cylindrical inner wall 40 and a scalloped outer wall 42 having semi-cylindrical depressions 44 having radii equal to the radius of the outer wall of the tubes 36. A pair of rings identical with 15 the ring 32 is placed in spaced relationship and a plurality of tubes is positioned about these rings with the ends of the tubes in the semi-cylindrical recesses 44, as indicated in Fig. 7. Recesses 44 are so spaced that when tubes are mounted in 20 these recesses, the side walls of the tubes contact each other, as clearly shown in Fig. 7. While these tubes are held in this position, their contacting walls are welded or soldered together to 25 form a unitary cylindrical structure and the ends of these tubes are welded or soldered to the rings 32 and 34.

After this welding operation has been completed, the heat exchanger is placed in a lathe or similar machine and the rings are turned down 30 so that the inner walls of these rings have the same diameter as the innermost portions of the walls of the tubes 36. In other words, the rings are turned down from the size shown in Figs. 6 and 7 to that shown in Fig. 8. The purpose of 35 turning down the rings in this manner is to permit a muffler freely to be slid in and out of the heat exchanger in a manner to be hereinafter described.

The tubes 36 form a scalloped, cylindrical 40 chamber within which a muffler 46 is located. This muffler comprises a sheet metal shell 48 divided into a plurality of compartments by partitions 50. These compartments are filled with sound absorbing material 52, such as glass wool or stainless steel wool and perforations 54 in the muffler shell provide acoustic couplings between the interior of these compartments and the gas passages 56 formed between the muffler shell and the tubes 36.

50 The end wall 58 of the muffler has attached thereto, by bolts 60, or in any other suitable manner, a heat insulating disc 62 of refractory or other suitable material which serves to protect the sound absorbing material against the intense heat of the combustion chamber.

The muffler 46 may be freely inserted into or removed from the heat exchanger 22. This muffler is secured in position in the heat exchanger by a bolt 64 attached to the end plate 66 of the muffler. This bolt 64 has a reduced threaded end 68 which passes through a sleeve 10 mounted in an opening in the wall of an exhaust tube 72, the bolt being secured to this sleeve by a nut 74. The tube 72 is bolted or otherwise secured to a plate 76 bolted to the ring 34 10 of the heat exchanger.

The casing 26 has a tapered outlet end 78 terminating in a short, cylindrical section 80 which may discharge heated air directly into an airplane cabin or other space to be heated or may be connected to a duct system for delivering this heated air to one or more outlets arranged in the same or different spaces. A carburetor air inlet pipe 82 has one end attached to the tapered outlet 78 and diverts part of the air which has passed over the heater into a carburetor 84 located outside of the casing 26. Pipe 86 connects the carburetor 84 with any suitable source of fuel and an induction tube 88 conducts the fuel and air mixture formed in the carburetor 84 to the combustion chamber 16. This induction tube has a reversely curved portion 90 leading to a long, straight end 92, which extends through the casing 26 and into the lower portion of the combustion chamber. All parts of the induction tube 88 preferably lie in the same horizontal plane and the straight end of this tube is given a length substantially seven times the internal diameter of this tube in order that the flow of fuel and air in different parts of the cross section of this tube will be substantially uniform at the point where the tube discharges into the combustion chamber.

That portion of the induction tube which lies within the combustion chamber receives heat from the combustion in this chamber and serves to preheat the fuel and air mixture delivered to this chamber. This portion of the induction tube extends across the lower portion of the combustion chamber in a direction perpendicular to the axis of this chamber so that mixture delivered by this tube tends to whirl about the axis of the combustion chamber and form a ring of flame therein when ignited by an electrical igniter 94 located in a pocket 96 which is outside of the combustion chamber but connected thereto by way of inlet 98 and outlet 100. The particular construction and arrangement of the induction tube and igniter are claimed in my co-pending applications, Serial No. 477,080, filed February 25, 1943, now Patent No. 2,433,618, Serial No. 477,081, filed February 25, 1943, now Patent No. 2,390,380, and Serial No. 484,971, filed April 29, 1943, now Patent No. 2,405,317.

After the heater has been in operation for an appreciable length of time, the air supplied to the carburetor 84 becomes heated and this heated air prevents the formation of ice in the carburetor and also assists in vaporization of fuel supplied to this air by the carburetor jet. When the heater is first started, however, the air supplied to the carburetor is cold and all of the fuel mixed with this air may not be completely vaporized. In order that the heater may start easily, it is desirable that any liquid fuel or exceedingly rich mixture of fuel and air be directed into the pocket 96 containing the igniter 94, as the heat of this igniter will vaporize the liquid fuel and readily ignite the resulting mixture of fuel and air.

I have accordingly provided a split spiral ring

102 which is attached to the circular wall of the combustion chamber, as by welding or any other suitable manner, and which serves to direct into the inlet 98 of the igniter pocket any liquid fuel or particularly rich mixture of fuel and air discharged from the induction tube 92. That end of the ring 102 which is adjacent the induction tube 92 is spaced from the rear wall 18 of the combustion chamber a distance substantially equal to the outside diameter of the induction tube, whereas the other end of this ring lies adjacent the igniter pocket 96 and is spaced from the wall 18 a distance substantially equal to the width of the inlet and outlet which connect this pocket with the combustion chamber. After the heater is in operation, this ring insures that any liquid fuel delivered to the combustion chamber will be vaporized and burn before it leaves this chamber.

20 The hot products of combustion flowing from the open righthand end of the combustion chamber 16 are directed by the muffler 46 into the gas passages 56 formed between the muffler shell and the tubes 36. As the hot gases flow along these 25 passages, these gases give up their heat to the walls of the tubes 36 and the cooled products of combustion leave the righthand ends of the passages 56 and enter an outlet chamber 104 formed between the righthand end of the muffler and the plate 76. These cooled gases then pass to atmosphere through discharge tube 72 and any suitable exhaust pipe which may be attached thereto. Sound entrained in the hot products of combustion 30 enters the muffler shell through perforations 54 and is absorbed by the sound absorbing material contained in the several compartments of the muffler.

35 Air supplied to the heater by the blower 12, or by any other suitable air supply means, passes 40 around the combustion chamber 16 and absorbs some heat from the walls of this chamber. Part 45 of this air then enters the lefthand ends of the tubes 36 of the heat exchanger while the remainder of this air enters the space 106 between these tubes and the casing 26. As the air flows lengthwise of the heat exchanger, this air absorbs 50 heat from the walls of the tubes 36 which functions like fins to transfer heat from the hot products of combustion to this air.

55 In the embodiment of Figs. 1 to 4, inclusive, the tubes 36 are provided with webs 108 which divide the tubes into two sections and facilitate the transfer of heat to the air flowing through these tubes. In the embodiment of Fig. 5, the tubes 36' are not provided with such webs, but in other respects the embodiment of Fig. 5 is identical with that of Figs. 1 to 4, inclusive.

Most of the heated air passes from the heat exchanger through the heater outlet and into an airplane cabin or other space or spaces to be heated. A small proportion of this heated air, however, is diverted into the carburetor inlet pipe 82 and flows to the carburetor 84, where it is mixed with fuel. This mixture then passes 60 through the induction pipe 88 to the combustion chamber 16 and is burned therein.

While the heat exchanger may be made of any suitable material, the tubes of which this heat exchanger is formed are preferably of material having a high heat conductivity, such for example as copper or aluminum, since the walls of these tubes act as fins to transfer heat from the hot products of combustion to the ventilating air. Where these tubes are provided with webs like the webs 108, 70 these webs should also preferably be of material

having a high heat conductivity. There are now available on the commercial market aluminum tubes which are already coated with aluminum metal alloy which melts at a temperature approximately 40° below the melting point of aluminum.

The heat exchanger can be readily made by cutting these commercial tubes to the desired length, stacking such tubes in the supporting rings 32 and 34, in the manner indicated in Fig. 7, placing a band around the tubes to hold them in this assembled relationship, bonding the tubes with a suitable flux at the points where the interior walls of these tubes engage each other, and placing the assembly in an oven maintained at a temperature between the melting point of the welding material and the melting point of aluminum. After the assembly has been kept in the oven the desired length of time, it is removed and cooled, at which time the tubes will be welded into a solid mass which is rigid and self-supporting. Thereafter the supporting rings can be turned down, as indicated in Fig. 8, to complete the heat exchanger.

While I have described my invention as being particularly adapted for heating the cabins of aircraft, it is not limited to such use and is capable of general application. It is to be understood that my invention is not limited to the particular details shown and described herein, but may assume numerous other forms and that the scope of my invention is defined in the following claims.

I claim:

1. A heater of the class described, comprising a heat exchanger composed of a plurality of individual tubes longitudinally extending in side by side contacting relationship and having their contacting portions secured to each other to form a gas tight tubular structure, said tubes having webs therein, each web having opposite edges secured to the walls of its tube throughout substantially the length of said tube, means forming a combustion chamber for supplying hot products of combustion to the interior of said tubular structure, a casing enclosing said heat exchanger in spaced relation thereto, and means for supplying ventilating air to said tubes and to the space between said tubes and said casing.

2. A heater of the class described, comprising a heat exchanger composed of a cylindrically arranged series of contacting cylindrical tubes longitudinally extending in side by side contacting relationship and having their contact portions secured to each other to form a gas tight tubular structure, a cylindrical muffler located in said heat exchanger in spaced relation thereto and cooperating with said tubes to form gas passages longitudinally of said heat exchanger, means forming a combustion chamber for supplying hot products of combustion to one end of said passages, and means for directing ventilating air over said combustion chamber means and through said tubes.
3. That method of making a heat exchanger which comprises forming a pair of tube supporting rings with scalloped outer peripheries, assembling a plurality of tubes about said rings with the ends of said tubes in scalloped portions of said peripheries and the side walls of adjacent tubes in contacting engagement with each other, securing the contacting walls of said tubes to each other and securing said tubes to said rings, and removing the internal diameters of said rings to make the internal diameters thereof conform to the innermost portions of the tubular structure formed by the innermost portions of said tubes.

HENRY J. DE N. MCCOLLUM.
